MIRROR PROVIDED LIPSTICK RECEPTACLE

Le Roy H. Fontan, Rutherford, N. J.

Application September 30, 1936, Serial No. 103,279

4 Claims. (Cl. 132—79)

My present invention relates to cosmetic receptacles and more particularly to an improved combined lipstick receptacle and mirror.

My invention is designed to combine in a single structure a two-part cosmetic receptacle such as a lipstick receptacle in which the lipstick holding element is ordinarily housed within a cover carrying a mirror. In carrying out my invention I provide a lipstick holder for carrying a supply of lipstick cosmetic and means for slidably moving the lipstick longitudinally of the holder. This holder is adapted to be housed within a cover or housing which normally protects the lipstick cosmetic when not in use, and an integral part of the cover or housing serves as means for engaging the feed device for the lipstick cosmetic to bring the lipstick cosmetic into housing position in its holder and within the receptacle itself when the receptacle is placed within the housing.

Fitting into a recess formed in one side of the lipstick housing is a mirror of superficial dimensions practically coextensive with the dimensions of one of the sides of the cover or housing and which mirror may be employed by the user of the lipstick cosmetic to guide her in the use of the cosmetic. Forming an integral part of the cosmetic holder is a spaced cover plate which, when the lipstick holder is housed within the cover or housing, is guided over the mirror and shields the same from dirt, abrasives and the like when the device is not in use.

A feature of my invention is an improved cosmetic receptacle and holder.

35 A feature of my invention is an improved combined cosmetic holder and receptacle.

A feature of my invention is an improved combined lipstick receptacle and mirror.

In the accompanying drawing,
40 Fig. 1 is a perspective view of a combined lipstick receptacle and mirror embodying my invention and illustrating the manner of manipulating the same.

Fig. 2 is a side elevation of the lipstick receptacle and enclosing casing therefor shown in a separated position and with the lipstick cosmetic protruding outward from the receptacle.

Fig. 3 is a bottom plan view of Fig. 2.

Fig. 4 is an assembly view of the lipstick cosmetic receptacle and enclosing holder showing the same in telescoped position.

Fig. 5 is a sectional side elevation on the line 5—5 of Fig. 4, and

Fig. 6 is a sectional end elevation on the line 55 6—6 of Fig. 5.

Referring to the drawing, 10 designates a lipstick receptacle of any desired contour in cross-section but preferably rectangular, provided on one face thereof with an elongated slot 11. One end of the receptacle is closed as by the end plate 12. Slidably mounted within the receptacle 10 is a cosmetic stick carrier 13 in which is fitted or held the inner end of a stick cosmetic 14. Extending laterally outward from one face of the carrier 13 is a stud 15 which extends through the slot 11 and is provided with a head 16 and by means of which the carrier 13 may be moved longitudinally of the receptacle 10, thereby moving the lipstick cosmetic 14 into the position shown in Figs. 2 and 3, or into the position shown in Fig. 5.

The end plate 12 is of greater superficial area than the area of the end of the receptacle 10 and one side thereof is offset with respect to the receptacle 10, as shown for example in Fig. 2, 20 and attached thereto and parallel to and spaced apart from the adjacent face of the receptacle 10 is a cover plate 17 backed by a reinforcing plate 18, as clearly shown in Figs. 2 and 5.

19 designates a cover or housing for the receptacle 10. One end of the cover or housing 19 is open, and the other end is closed by a plate 20 which may be and preferably is formed integral with the housing 19. The lipstick cosmetic receptacle 10 has a sliding fit within the cover or housing 19. On one face or side of the housing 19 is formed a slot 21 which is adapted to engage with the head 16 of the stud 15 when the receptacle 10 is slid into the cover or housing 19 thereby moving the cosmetic carrier 13 to a position adjacent the end plate 12 and thereby bring the stick of cosmetic 14 within the limits of the receptacle 10.

The portion of the cover or housing 19, opposite the side of the housing in which is formed the slot 21, is inset within the limits of such cover or housing, as clearly shown in Fig. 6, such side being designated for convenience by the reference numeral 22. This member 22 defines, in collaboration with the upper end of the side members of the housing 19, a recess in which is fitted a mirror 23.

The mirror 23 is substantially equal in length to the length of the cover or housing 19 and is of a width substantially equal to the width of the member 22. Also the combined thickness of the side 22 and mirror 23 is slightly less than the space between the cover plate 17 and the adjacent face of the receptacle 10. It will therefore be apparent that when the receptacle 10 is

telescoped into the cover or housing 18 the cover plate 17 will move over and enclose the mirror 23, protecting the same from possible injury or breakage.

5 Because for construction reasons it is desirable
to have the cover plate 17 of less length than
the receptacle 10, I find it advantageous to place
in the space between the side walls of the hous-
ing 18, above the mirror 23 and adjacent to the
10 end wall 20 a plate 25 against which the end of
the cover plate 17 abuts, as clearly shown in
Figs. 4 and 5.

When it is desired to use the combined lipstick receptacle and mirror the person operating the same will ordinarily grasp the cover or housing 19 in the left hand, as shown in Fig. 1, and with the receptacle 10 grasped in the right hand, as shown in Fig. 1. The cover housing 19 and receptacle 10 are then separated from each other as shown in Fig. 1 and the operator by moving the stud 15 slides the lipstick cosmetic 14 out of the receptacle 10 into the position illustrated in Figs. 1, 2 and 3. The lipstick cosmetic 14 is then manipulated, the operator holding the cover or housing 19 in such a position as to enable her to view the part of her face to which the lipstick cosmetic 14 is being applied.

The operation of applying the lipstick cosmetic being completed, the operator may return the lipstick cosmetic 14 to its position within the receptacle 10, or may push the receptacle 10 into the cover or housing 19 without first so doing, thereby bringing the head 16 of the stud 15 into engagement with the end of the slot 21, whereupon further movement of the receptacle 10 to a position within the cover housing 19 will force the lipstick cosmetic 14 into position within the receptacle 10. Also simultaneously with the movement of the receptacle 10 to a position within the cover or housing 19 the cover plate 11 will move into position in the cover or housing 10 and over the mirror 23 and therefore into a position to protect the mirror 23 from possible injury or damage.

45 Whereas I have described my invention by reference to specific forms thereof, it will be understood that many changes and modifications may be made without departing from the spirit of the invention.

I claim:

1. In a device of the kind described the combination of a cosmetic holder, a cover into which the cosmetic holder telescopes to protect the

same when not in use, a mirror carried by the cover, and a cover plate carried by the cosmetic holder and enclosing the mirror when the cosmetic holder is telescoped to a position within the cover.

2. In a device of the kind described the combination of a cosmetic holder provided with a slideable carrier for receiving and holding a stick of cosmetic, a cover plate carried by the cosmetic holder and spaced apart therefrom, a cover for said cosmetic holder into which the cosmetic holder telescopes to protect the cosmetic when not in use, a mirror carried by said cover and slideable into the space between the cover plate and cosmetic holder and forming a protective cover for the mirror. 10 15

3. In a device of the kind described the combination of a cosmetic holder provided with a cosmetic carrier movable longitudinally thereof to expose the cosmetic for use, a cover plate arranged parallel to the holder and spaced apart therefrom to define a recess, a cover for said holder slideable onto the holder in telescope relation therewith to house the holder when the cosmetic is not in use, a mirror secured to the outer face of the cover, a guideway arranged in the walls of the cover in alignment with the cover plate carried by the holder and adapted to receive the cover plate to protect the mirror when the holder and cover are arranged in telescope relation with respect to each other. 20 25 30

4. In a device of the kind described the combination of a multi-sided cosmetic holder provided with a cosmetic carrier slidably mounted with relation thereto, a protecting cover plate 35 secured to the holder and arranged parallel to and spaced apart from one of the sides of said holder, a multi-sided cover arranged to receive the multi-sided holder in telescopic relation to protect the cosmetic when the device is not in use, one of the sides of the cover being parallel to the opposite face and lying below the edges of the adjacent sides to define a trough on one side of the cover, a mirror resting on and secured to the outer face of the side forming the bottom of the trough, and grooves formed on the inner face of the opposite sides forming the trough and adapted to receive as a sliding fit the cover plate of the holder, the side forming the bottom of the trough and the mirror slidably into the space between the cover plate and the side of the cosmetic holder. 40 45 50
